PORTABLE FLUORESCENT LAMP

Harold Akroyd, Denton, near Manchester, England, assignor to Oldham and Son Limited, Denton, near Manchester, England, a British company

Application November 23, 1948, Serial No. 61,560

5 Claims. (Cl. 240—10.6)

1

This invention relates to means for operating fluorescent lamps.

A main object of the invention is to devise a means of operating a fluorescent lamp from an accumulator.

A further main object is a lighting unit embodying a fluorescent lamp supplied by an accumulator which is adapted for use in coal mines.

The invention consists in means for operating a fluorescent electric lamp from a source of direct current of voltage substantially less than that required to operate the lamp, the means comprising in combination connections for the direct current supply, a vibratory make and break device for the current, a holder or holders for the lamp and a step-up transformer the primary winding of which is serially connected to the current interrupter and the connections for the direct current supply, and the secondary winding of which is connected to the said holder or holders for the lamp, the ratio of the transformer windings being such as to give a secondary voltage sufficient to start and operate the lamp.

The invention also consists in a transportable electric lighting unit which is substantially flameproof and employs a fluorescent lamp or lamps, the said unit comprising an accumulator or accumulators having sealed cells and giving a voltage substantially less than that required to operate the fluorescent lamp or lamps, and means according to the preceding paragraph, the said lamp or lamps, accumulator or accumulators and the said means being enclosed in a substantially flameproof casing provided with a window for emission of light from the lamp or lamps with terminals accessible outside the casing for recharging the cells and with openings venting the accumulator cells to atmosphere.

The fluorescent lamp circuit may be rendered stable in the usual way by chokes, resistances, or condensers, or alternatively, by a combination of these components.

Preferably, the accumulator is connected to the centre of the primary of the transformer, the two ends of the primary being connected to the two contacts respectively of the vibrator which are closed alternately, whereby the intermittent current is alternating.

Alternatively, two fluorescent lamps, each with a transformer, may be supplied with unidirectional intermittent current by connecting one pole of the accumulator to the end of the primary of each transformer, and the other pole to the common contact of the vibrator, while the

2

other ends of the primaries are connected to the two contacts of the vibrator which are closed alternately, thereby the intermittent current is supplied to the two lamps alternately, and, if the two lamps are close together, flickering is avoided.

In the case of lamps requiring preheating, the preheaters may be supplied from the secondary of the transformer or directly from the accumulator, being put into circuit by a starting switch which is opened as soon as the discharge starts.

In the usual commercial form of fluorescent lamp, the discharge terminals are in the form of cathodes and are adapted to be preheated. A typical 10 inch tube which has an operating voltage of about 54 volts, requires a striking voltage of about 90 volts, while the preheating circuit requires a current of about double the tube current at 54 volts.

According to the invention, for supplying a fluorescent lamp of this type, the transformer is designed with a regulation characteristic of secondary volts falling rapidly with the load, the voltage being the normal operating voltage at the load of the lamp, a high voltage adequate for striking at no load, and a low voltage adapted to the preheating circuit at the high load of the preheating circuit. A transformer with this characteristic will render the lamp circuit stable without the use of auxiliary choke or resistance.

The transformer is preferably given this characteristic by giving it high reactance, but alternatively, by introducing resistance into its windings or circuit.

The operating means for fluorescent lamp according to the invention comprises a main switch and a starting switch. The main switch closes the circuit from the accumulator to the centre of the transformer, while the ends of the primary are connected to the two contacts of the vibrator which are alternately closed. The driving magnet of the vibrator is in a shunt circuit from one contact to the accumulator. Thereby alternating current is supplied to the primary of the transformer. The secondary of the transformer is connected to the discharge terminals of the lamp which, in the said type of lamp, constitute one terminal of the cathode. The starting switch is adapted to close the preheating circuit of the cathode.

When the starting switch is closed, the high preheating load is put on the secondary and its voltage drops to the value required. When the switch is opened, there is no load on the secondary, and its volts rise to the high voltage required

for striking. As soon as the discharge starts putting a load on the transformer, its volts drop to normal operating volts.

During the useful period of discharge of a lead accumulator, the voltage falls substantially, for instance, from 2.2 to 1.8 volts per cell. This variation of voltage is more than is suited to proper operation of a fluorescent tube. A regulator, therefore, is included in the accumulator circuit, adapted to maintain an approximately constant current in the primary of the transformer while the accumulator voltage falls during its period of discharge. This regulator may be a barretter of usual type, employing an iron wire of which the resistance increases rapidly with temperature.

In order that the invention may be more clearly understood, reference will now be made to the accompanying drawings which show by way of example, preferred embodiments thereof and in which:

Fig. 1 is a diagram showing means for operating two fluorescent lamps operated from one accumulator through the intermediary of one vibrator;

Fig. 2 is a front elevation partly in section through line II-II of Fig. 3 of a transportable lighting unit suitable for use in atmospheres where there is danger of inflammation or explosion, especially in a coal mine;

Fig. 3 is a side elevation of the unit partly in section on line III-III of Fig. 2, and

Fig. 4 is a plan view of the unit with the left hand half of the top wall removed.

A current interrupter in the form of a vibrator 44 consisting of a reed 1, fixed at one end to a block 2, carries at the other end an armature 3 adapted to vibrate before the pole-piece of the driving magnet 4. Contacts 5 on the reed are adapted to make contact alternately, as the reed vibrates, with the two fixed contacts 6. Quench circuits 7 bridge the contact gaps.

A 6 volt accumulator 8 is connected to the reed through a main switch 9 and a barretter 10. The coil of the magnet 4 is connected to the reed and to one of the fixed contacts 6. The other pole of the accumulator 8 is connected to the centre tap of the primary winding 11 of a transformer 43 associated with the lamp L1, the two fixed contacts 6 are connected, respectively to the two ends of the primary 11, and the terminals of the secondary winding 13 are connected to the discharge terminals 15 of the lamp L1. The discharge terminals 15 are in the form of pre-heater cathodes, each with terminals 14 and 16. The secondary is connected to the terminals 14, while the terminals 16 are connected together through a contact 17 of a starting switch 18. A suitable condenser 12 is connected across the secondary winding 13 of the transformer to improve the operating characteristics of the transformer.

The circuit including the vibrator, the lamp L1, and the associated transformer 43 is duplicated from another pair of contacts on the same vibrator to incorporate the lamp L2.

To cause operation of the lamp L1 a respective pair of movable contacts 5a are mounted on the reed in operative relation with fixed contacts 6a connected to the ends of the respective primary winding. The transformer and its primary winding associated with the lamp L2 and the respective secondary winding and condenser are indicated by the references 43a, 11a, 13a and 12a respectively, the cathodes 15a of the lamp L2 be-

ing connected in circuit in manner identical with that described with reference to the lamp L1, the preheater circuit being controlled by contact 11a corresponding to the contact 17 already referred to with reference to lamp L1.

The two fluorescent tubes indicated at L1 and L2 are of identical design.

The circuits may be traced as follows: for normal operation, from the positive pole of the accumulator 8, through the main switch 9, the barretter 10, the reed 1, the pair of contacts 5, 6, to the left hand portion of primary 11 of the transformer associated with lamp L1 and from the centre thereof to the other pole of the accumulator. At the next vibration of the reed, the circuit deviates through the other pair of contacts 5, 6, through the other half of the primary 11.

The circuit through the driving magnet 4 is from the accumulator through main switch 9, through starter switch contacts 19 hereafter referred to, to the reed 1 and thence through the magnet coil to the primary of the transformer 11, and back to the accumulator. This circuit is intermittent since the drive coil is short circuited when the left hand contacts 5, 6 (as viewed in the diagram) are closed.

On closing the main switch 9 current flows through the barretter 10, the reed 1, and the driving magnet 4 through the left hand half of the primary winding 11 back to the accumulator, thus causing excitation of the driving magnet 4 and consequential vibration in the reed 1. As a result of vibrating the reed 1, the contact 5 engages the left hand contact 6, thus the drive coil is short circuited and current flows through the left hand half of the primary winding inducing current in the associated secondary 13. Simultaneously, the contacts 5a engage the fixed contacts 6a, and current flows first through one half of the primary winding 11a inducing flow through its associated secondary 13, and in the next movement of the reed 1, due to its own resiliency, the left hand contacts are opened and the right hand contacts 5a, 6a are closed, causing the other half of each primary to be energised and simultaneously to short circuit the driving magnet 4.

The starting switch 18 is then operated and closes the two pairs of contacts 17 and 11a thus closing the circuits through the preheating cathodes of the respective lamps L1 and L2.

The barretter 10 is associated with the contacts 19 of the starting switch, so that when the starting switch is closed the contacts 19 are closed, the function of the contacts 19 being to short circuit the barretter 10 during the pre-heating period which persists as long as the starting switch is held in the closed position. On releasing the starting switch the contacts 17, 11a and 19 are opened so that the barretter is again in circuit to regulate the output of the accumulator. The starting switch 18 may be in the form of a press button switch designed to cause simultaneous operation of the contacts 17, 11a and 19.

Clearly, a further lamp may be actuated from the reed 1 by adding thereto suitable movable contacts associated with appropriate fixed contacts for the respective transformer primary. Alternatively, the vibrator may control but one fluorescent lamp by utilising the circuits described with reference to the lamp L1 illustrated in the accompanying diagrammatic drawing.

From the foregoing it will be observed that a

feature of the embodiments described is that the alternating current supplied to the fluorescent lamps provided by the respective transformers is separate and distinct in each case, although the storage battery supply and the vibrator is common to all the lamps, thereby the operation of any lamp in the arrangement described is independent and faults in a transformer or in a lamp are restricted in effect to the transformer and lamp affected.

Further, although in the embodiment described exactly similar lamps are referred to, clearly, the invention comprises the employment of lamps of different types or sizes, provided that appropriate transformers are designed to suit the operating conditions of the respective lamps. Although the use of a single barretter is described, the invention comprises the employment of a barretter in the supply line of each transformer, for example, in the accompanying diagram a barretter may be inserted between the line and the central tap of each transformer. In such cases provision will be made for short circuiting the barretters when the starter switch is operated to close the contacts such as 17, 17a.

By the present invention simple and effective operating means for fluorescent lamps in which the primary voltage is obtained from accumulators is achieved and a transportable unit may be provided adapted to receive the accumulator and the fluorescent lamps which unit comprises a housing for the accumulator, mountings for the lamps, and the necessary circuit connections and switches, and portability can in fact be obtained by employing accumulators of low voltage, for example 6 volt accumulators and consequently minimum weight, ease of maintenance (having in mind the necessary operation of topping the accumulator) and simplicity of construction is achieved.

When a lighting unit is to be used in coal mines the vibrator is in a sealed case, and it and the switch and the terminals of the fluorescent tube and connections are enclosed in a sealed case combined with the accumulator case. The accumulator may be arranged to be charged without removing its cover, because a joint of the size required for a multi-cell accumulator is liable to deteriorate with frequent opening and cease to be flameproof. For this purpose, flameproof vents are made from the space above the accumulator to atmosphere, through which gases generated during charge can escape. Further, the charging terminals may be made accessible outside the sealed casing, one at least being rendered inaccessible when the unit is in the mine, or being disconnected inside the casing from the accumulator.

The fluorescent tube or tubes are within the sealed case behind a glass forming part of the wall of the sealed case.

The transportable self-contained light unit comprises a casing of light metal consisting of a container 20 provided with bosses 21 carrying a handle 22, and an upper portion or lid 23 which is attached to the container by screws 24. A suitable gasket (not shown) may be included between the container and lid to render the casing flameproof when assembled. The container holds the accumulators 8, which may take the form of double cell units 25 in cases 26 of hard rubber or plastic. The plates 27 of the cells are attached in conventional manner to bars 28 which are joined to lugs 29 passing in gas-tight manner through the closures 30 of thermoplastic sealing 75

composition. Vents 31 of the cells are provided with tubes 32, which are also sealed in the closure 30 and pass to openings 33 in resilient caps 34 held on the outside of the container 20 by means of metal retaining members 35. Each cell is thus sealed from the inside of the casing and is vented to atmosphere outside the casing, and may be recharged in situ when the casing is closed. Straps 36 serve to connect serially cells of each

10 accumulator and connections (not shown) are made from remaining lugs 29 to connect the accumulators in series. The outermost lugs of the accumulators may be connected to insulated sockets into which plugs carried by the lid 23 will fit on attachment of the lid to the container.

The lid 23 is provided with a rebated opening to receive a reflector 37, and a window 38, preferably of armour plate glass, which are retained in position by a metal frame 39 bearing on the 20 window through the medium of a gasket 40. The frame 39 is attached to the lid by screws 41. The lid is also provided with a shelf 42, to which are attached transformers 43, vibrator 44 (on a raised portion of the shelf) and brackets 45 having clips 25 46 to hold the fluorescent lamps L1 and L2.

In openings in the upper wall of the lid 23 are fitted the main switch 9 and the starting switch 18. Suspended from the shelf 42 by means of screws 49 is a board of insulating material 50 30 serving to carry condensers 51 and resistances 52.

The raised portion of the shelf is sufficiently high to allow the top of the vibrator 44 to protrude through an aperture in the upper wall of lid 23, and a cap 54 retained in position by screws 35 55 is provided to cover the aperture, a gasket 56 being included between the flange of the cap and the wall of the lid. The cap 54 allows of ready removal of the vibrator for replacement.

The accumulators are connected by way of 40 the main switch 9, barretter (if used) and vibrator 44 to the primary windings of the two transformers 43 by connections arranged as shown in Fig. 1, and connections from the secondary windings of the said transformers to the fluorescent lamps L1 and L2 and to the heater windings of the said lamps are provided as 45 described above.

Charging terminals for the accumulators (not shown) are arranged to be accessible from the outside of the casing, one or both being adapted to be rendered inaccessible when the lighting unit is ready for use.

The above construction allows of a transportable lighting unit being produced with a weight of approximately 25 lbs. and a light output of substantially 13 lumens per lb. weight of the unit (assuming an overall efficiency of 50 per cent). The unit may be recharged close to the coal face in mines by employing suitable charging stands.

Instead of producing alternating flow through the primary windings 11, 11a a pulsating individual flow can be produced as will be well understood in the art.

65 I claim:

1. A self-contained transportable electric lamp unit comprising a casing including a body portion and a cover portion having a window therein, means sealing said casing to render it flameproof, a re-chargeable battery in said body portion, vent means from said battery and opening through said body portion to atmosphere, a shelf in said cover portion, lamp supports on said shelf and having contacts for supporting a lamp behind said window, vibrator means on said

shelf, a circuit connecting said vibrator means between said battery and said lamp support contacts, and switch means on said casing and interposed in said circuit for actuating a lamp in said supports.

2. A self-contained transportable electric lighting unit comprising a casing including a body portion and a cover portion removably mounted on said body portion, a closed light transmitting window in said cover portion, means sealing said casing to render it flame-proof, a rechargeable battery in said body portion, vent means from said battery and opening through said body portion to atmosphere, a shelf in said cover portion, a reflector in said cover portion and mounted on said shelf behind said window, lamp support means including contacts and mounted on said shelf to support a lamp between said reflector and said window, vibrator means on said shelf behind said reflector, a circuit connecting said vibrator means between said battery and said lamp support contacts for energizing a lamp mounted in said lamp support means, and switch means on said casing and interposed in said circuit for actuating a lamp in said support means.

3. A self-contained transportable electric lighting unit as defined in claim 2 wherein said cover portion is provided with an opening immediately adjacent said vibrator means for ready access thereto, and a closure removably sealed over said opening.

4. A self-contained transportable electric lighting unit comprising a casing including a body portion and a cover portion removably mounted on top of said body portion, a closed light-transmitting window in said cover portion, means sealing said casing to render it flame-proof, a rechargeable battery in said body portion, vent means from said battery and opening through said body portion to atmosphere, a

5

25

shelf in said cover portion, a reflector mounted on said shelf behind said window, lamp support means on said shelf, a pair of lamps supported by said lamp support means between said reflector and said window, said lamps being operated at a higher voltage than that of said battery, a transformer for each lamp mounted on said shelf behind said reflector, a vibrator unit mounted behind said reflector and between said transformers, said vibrator unit being connected between said battery and both of said transformers and switch means connected between said battery and said vibrator means for controlling operation of said lamps.

5. A self-contained transportable electric lighting unit as defined in claim 4 wherein said cover portion has an opening and said vibrator unit extends through said opening, and a cap removably sealed to said cover portion around said opening and enclosing said vibrator unit but permitting ready access thereto.

HAROLD AKROYD.
